[57] CLAIM

The ornamental design for a wrist mounted holder for pins and other metal objects, as shown and described.

DESCRIPTION

FIG. 1 is a top, front, right side perspective view of a wrist mounted holder for pins and other metal objects showing my new design;

FIG. 2 is a top plan view thereof;

FIG. 3 is a side elevational view thereof;

FIG. 4 is a bottom plan view thereof;

FIG. 5 is a rear elevational view thereof; and

FIG. 6 is a front elevational view thereof.
